UNITED STATES PATENT OFFICE.

GLEB W. DERUJINSKY, OF NEW YORK, N. Y., ASSIGNOR TO STERLING BRONZE COMPANY, OF NEW YORK, N. Y., A CORPORATION OF NEW YORK.

DESIGN FOR AN EMBLEM FOR AUTOMOBILE HOODS AND RADIATORS.

Application filed November 10, 1925. Serial No. 15,398. Term of patent 14 years.

To all whom it may concern:

Be it known that I, GLEB W. DERUJINSKY, a citizen of Russia, residing at the city of New York, borough of Manhattan, county and State of New York, have invented a new, original, and ornamental Design for Emblem for Automobile Hoods and Radiators, of which the following is a specification, reference being had to the accompanying drawing, forming part hereof.

Figure 1 is a side view of an ornament for an emblem for automobile hoods and radiators showing my design.

Figure 2 is a front view of an ornament for an emblem for automobile hoods and radiators showing my design.

I claim:

The ornamental design for an emblem for automobile hoods and radiators, as shown.

GLEB W. DERUJINSKY.
